WIRE FRAME FOR GARMENT HANGERS

Donald W. Doherty, Crystal Lake, Ill., assignor to
Queen Manufacturing Co., Inc., Chicago, Ill., a
corporation of Illinois

Application September 8, 1951, Serial No. 245,693

2 Claims. (Cl. 211—119)

1

This invention relates to improvements in wire frames for garment hangers of the kind in which an enclosing bag is supported on the frame, from which a plurality of garments may be suspended within the bag. More particularly, the invention relates to the hinged arrangement of the cross bar and the supporting hooks forming a part of the frame of the character above described.

Among the principal objects of the invention is to provide an improved and simple form of pivotal connection between the cross bar and one or more hooks, to obtain greater economy in the manufacture of such device.

A further object is to provide an improved form of pivotal connection for the hooks so as to permit the hooks to be collapsed or folded along and against the cross bar in such a manner as to facilitate the shipment of the frames in collapsed position, and so as to facilitate the assembling of the frames in the garment hangers.

Other objects and advantages will appear from time to time as the following description proceeds:

The invention may best be understood by reference to the accompanying drawings, in which:

Figure 1 is a perspective view of a garment hanger of the kind to which my invention relates;

Figure 2 is an enlarged perspective view of a hanger frame embodying my invention;

Figure 3 is an enlarged detail section taken on line 3—3 of Figure 2;

Figure 4 is a fragmentary plan view of the cross bar and hooks shown in Figure 3;

Figure 5 is a detail section taken on line 5—5 of Figure 4;

Figure 6 is a fragmentary plan view of a modified form of hinged connection for the hooks;

Figure 7 is a fragmentary side view of the hinged connection shown in Figure 6.

Referring now to the embodiment of the invention illustrated in the drawings, the frame 10 is constructed of wire of suitable gauge and rigidity to support the weight of the garment bag, indicated at 11. The bag 11 shown herein is of a rectangular cross section corresponding to the outline of the frame 10 so that the latter snugly fits within and supports the upper end of the bag when assembled therein. As is customary with devices of this kind, the frame is made separately from the bag and has one or more hooks 12, 12 hinged to a cross bar 13 connecting the longer side bars 14, 14 of the frame midway between the shorter side bars 15, 15 of the frame.

In the form of frame shown in Figure 2, two such hooks with their hinge connections are

2

shown; but it will be understood that garment bags of this kind are also commonly made with one or three such hooks, depending upon the size of bag desired.

5 The hooks 12 are designed to extend through apertures 16, 16 in the top of the bag when the device is in assembled position, as shown in Figure 1. When in assembled condition, the major portion of the cross bar 13 is preferably disposed in slightly spaced relation below the top of the bag and with its extreme ends bent upwardly for connection to the side bars 14, 14 of the frame, so as to facilitate the hanging of the individual garment hangers of conventional form (not shown) over the cross bar 13.

Referring now more particularly to the hinged construction for the hooks 12 on cross bar 13, the latter bar is formed with the proper number of Z-shaped bends, indicated at 20, 20 in spaced relation therealong to correspond with the number of supporting hooks to be hinged to the cross bar. Each Z-shaped bend 20 is disposed in a plane parallel with the general plane of the frame 10 with the central straight portion 21 thereof arranged transversely of and substantially at right angles to the general longitudinal axis of the cross bar 13. The opposite ends of the central straight portion 21 are bent inwardly and continue as relatively straight portions 22 which then curve into alignment with the cross bar 13 on its general longitudinal axis so that each Z-shaped bend as a whole may be considered as arranged at an angle of substantially 45 degrees to the general longitudinal axis of the cross bar.

35 The intermediate transverse portion 21 of the Z-shaped bends 20 provide hinge supports for eyes 23 which are preferably formed integrally with the shanks 12a of the wire hook members 12.

As will be seen from Figure 4, the wire portions 22, where they join the opposite ends of the transverse hinging portions 21 of each Z-shaped bend, form stops for holding the hook eyes 23 against lateral displacement so that the hinged movement of each hook 12 is in a plane substantially perpendicular to the general plane of the frame 10. The outer ends 12b, 12b of the hooks 12 are disposed in a plane generally perpendicular to the axis of pivotal movement of each hook so that the hook is permitted to swing through an angle of only 180 degrees on the upper side of the cross bar as the latter is assembled in the frame.

50 In order to permit substantially flatwise folding of the hooks 12 against the cross bar in both

directions, I find it preferable to offset the transverse hinge portion 21 slightly from the general axis of the cross bar and also arrange the eye 23 so that its major portion extends toward one side of the shank 12a. Where two hooks are used, as shown in the drawings, it will be observed that one hook can be swung in one direction with its shank 12a in overlapping position along the cross bar and that the other hook can be swung in the other direction with its shank in side-by-side relation along the cross bar and with its outer end partially lapping the first hook. In either case however, the swinging movement of the curved outer ends 12b of the hooks will be limited by the cross bar when the two hooks are in fully collapsed or folded position on the frame.

As a result of the arrangement just described, the hooks 12 can be folded along and against the cross bar for storage and shipment of the frames in collapsed position. It will be observed further that, since the hooks can only be swung toward the upper side of the frame through an arc limited to 180 degrees or less, it is impossible for any one, whether at the factory or in the home, to assemble the frame in a garment bag with the frame in an improper inverted position, where the cross bar extends above the level of the frame because, in each case, the hooks must be inserted through the apertures 16 in the top of the bag, which operation will automatically insure the proper arrangement of the frame with the cross bar disposed at a level below the top of the bag.

It will also be noted that, due to the limited degree of swinging movement of the hooks permissible with my improved construction, the frame alone can be readily stacked for storage in shipment with the hooks in folded position and, when separating the frames for assembly, the hooks of adjacent frames cannot become entangled with each other, as is the case with conventional frames where the hooks are permitted to swing through a full arc of 360 degrees.

In the modified form of hinge connection for the hooks shown in Figures 6 and 7, each Z-shaped bend 20a is arched or bent upwardly so that the transverse portion 21a of the bend is offset substantially above the horizontal plane of the main body of the cross bar 13a. This permits eyes 23a of the hook members to be hinged to the transverse portion 21a in such a manner that the shank of the hook can be swung in either direction toward the body of the cross bar without interference with the adjacent portions of the Z-shaped bend 20a. Accordingly, in this modified construction, the intermediate transverse portion 21a of the bend is not offset laterally of the longitudinal axis of the cross bar 13a. It is also unnecessary to offset the eye 23a from the shank of the hook as is the case with the form of hinge connection shown in Figure 5.

Although I have shown and described certain embodiments of my invention, it will be under-

stood that I do not wish to be limited to the exact constructions shown and described, but that various changes and modifications may be made without departing from the spirit and scope of the invention as defined in the appended claims.

I claim:

1. In a garment hanger support, an open frame and a wire cross bar rigidly connecting opposite sides of said frame, said cross bar being formed between its ends with a substantially Z-shaped bend with the intermediate transverse portion of said bend extending substantially at right angles to the general longitudinal axis of said bar and in a plane generally parallel to the plane of said open frame, and a supporting hook for said frame having an eye hinged on said intermediate portion, and an arcuate terminal hook portion, the said transverse intermediate portion of the Z-shaped bend including a portion which is offset laterally toward one side of the general longitudinal axis of said cross bar and whereon the eye of the hook is hinged to said portion, whereby the shank of said hook is collapsible into substantially parallel relation along one side of said cross bar when swung in one direction, but with the swinging movement limited by engagement of the arcuate hook portion with the cross bar.

2. In a garment hanger support, an open frame and a wire cross bar rigidly connecting opposite sides of said frame, said cross bar being formed between its ends with a substantially Z-shaped bend with the intermediate transverse portion of said bend extending substantially at right angles to the general longitudinal axis of said bar and in a plane generally parallel to the plane of said open frame, and a supporting hook for said frame having an eye hinged on said intermediate portion, and an arcuate terminal hook portion, the said transverse intermediate portion of the Z-shaped bend including a portion which is offset laterally toward one side of the general longitudinal axis of said cross bar and whereon the eye of the hook is hinged to said portion, whereby the shank of said hook is collapsible into substantially parallel relation along one side of said cross bar when swung in one direction, but with the swinging movement limited by engagement of the arcuate hook portion with the cross bar, the general axis of said cross bar being offset from the general plane of the frame.

DONALD W. DOHERTY.
